UNITED STATES PATENT OFFICE.

WILLIAM H. DAUGHERTY, OF JASONVILLE, INDIANA.

CAR-WHEEL.

974,363.

Specification of Letters Patent.

Patented Nov. 1, 1910.

Application filed January 4, 1910. Serial No. 536,432.

To all whom it may concern:

Be it known that I, WILLIAM H. DAUGHERTY, citizen of the United States, residing at Jasonville, in the county of Greene and 5 State of Indiana, have invented certain new and useful Improvements in Car-Wheels, of which the following is a specification.

This invention relates to journal bearings and refers particularly to a device especially 10 adaptable to railway cars of light construction.

The invention has for an object the provision of an improved journal bearing and wheel for interfitting with the same where- 15 by the wheel may be readily detached without removing the car from the track or of necessitating the complete withdrawal of the axle which supports the wheel.

The invention has for another object the 20 provision of a journal bearing which embodies strength and durability, as well as simplicity in construction, so as to produce a device of this nature which is applicable to mine cars where the same are subjected 25 to severe usage, and wherein it is necessary to provide means for detaching the wheels from the car without conveying the same to a general place for repairs.

For a full understanding of the invention 30 reference is to be had to the following description and accompanying drawings in which:—

Figure 1 is a transverse section through a mine car disclosing the improved journal 35 bearing and hub in section and attached to the same. Fig. 2 is a detailed sectional view of the journal bearing and hub in detached position and ready to be assembled, and Fig. 3 is a detailed perspective view of the 40 bearing and the hub of the wheel detached from one another.,

Corresponding and like parts are referred to in the following description and indicated in all the views of the accompanying draw- 45 ing by the same reference characters.

Referring to the drawing the numeral 10 designates the body of the mine car which is provided with the improved journal bearing consisting of the boxing 11 which is sup- 50 ported adjacent one end of the car 10, and at one side thereof through the medium of a web 12. The web 12 is preferably cast integral with the boxing 11 and extends upwardly from the outer end thereof for en- 55 gagement against the outer side of the body 10. Bolts or rivets 13 are engaged through

the web 12 and and the side of the body 10 to support the boxing 11 in position.

The inner end of the boxing 11 is provided with an annular bead 14 which provides a 60 groove 15 for the reception of a retaining strap 16 for engagement in the groove 15 between the bead 14 and the outer end of the boxing 11 to prevent the lateral play of the boxing incident to the jarring of the same 65 when the body 10 is in motion. The strap 16 is suitably secured against the bottom of the body 10. The outer end of the boxing 11 is provided with an overhanging flange 17 which is extended outwardly therefrom 70 and of the formation of a housing of an inverted U-construction to form a channel 18 within the inner wall of the same. The upper portion of the flange 17 is concentrically disposed with relation to the passage 19 75 provided through the boxing 11 and in which is inserted the outer end of an axle 20.

The improved hub, which is designated as 21 on the drawing, and which is adapted for engagement with the boxing 11, comprises 80 the usual hub structure with an inwardly extended and integrally formed collar 23 having a diameter corresponding to the inner face of the flange 17, whereby the collar 23 is permitted to rotate freely and is pre- 85 vented from lateral vibration therein. The inner end of the collar 23 is provided with a flange 24 which engages loosely in the channel 18 for the purpose of preventing the displacement of the collar 23 from the flange 17. 90

It will be observed from Fig. 1 that the axle terminates at a point centrally within the hub 21 to admit of the positioning of a threaded plug 25 in the outer end of the hub 21 which is correspondingly threaded to 95 retain the plug 25 in position. An angular head 26 is formed upon the outer end of the plug 25 for the reception of a suitable wrench, or like implement, by means of which the plug 25 is rotated to withdraw the 100 same from the hub 21.

In the operation of the device, when it is desired to withdraw a wheel from the body portion, the body 10 is raised slightly from the ground whereupon the plug 25 is re- 105 moved from the hub 21 and the axle 20 is driven inwardly through the collar 23 to a point beyond the inner face of the flange 24. This positioning of the axle 20 admits of the downward movement of the collar 23 in 110 the flange 17 to withdraw the flange 24 of the collar 23 from the channel 18 and to

thereby admit of the removal of the wheel 22. To effect this result, it is of course, necessary to remove the plug 25 from the opposite hub 21 to admit of the longitudinal 5 movement of the axle 20 through the opposite boxing 11.

Having thus described the invention what is claimed as new is:—

1. A journal bearing including a cylindrical boxing having an enlarged and overhanging flange at its outer end, the flange being interrupted at its lower side, a hub engaged against the box, an annular flange formed on the inner end of said hub for interlocking engagement with the overhanging flange, an axle loosely engaging through said boxing and said hub when registered to secure the same together, and a detachable plug carried in the outer end of said hub to retain the axle from displacement.

2. A journal bearing including a boxing having a web adjacent its outer end to seat against the side of a supporting body, and

having an overhanging flange outwardly of the web and being open at its lower side, said boxing also having spaced beads to provide a groove, a retaining strap seated in the groove and carried by the supporting member to secure the boxing thereto, a hub positioned against the outer end of the boxing, an annular flange formed over the inner end of said hub for interlocking engagement with the overhanging flange, an axle loosely engaging through said boxing and said hub when registered to secure the same together, and a detachable plug carried in the outer end of said hub to retain the axle from displacement.

In testimony whereof I affix my signature in presence of two witnesses.
